UNITED STATES PATENT OFFICE

FREDERICK HUGH AUSTEN, OF LEICESTER, ENGLAND, ASSIGNOR TO THE VENEERAY
INVISIBLE HEATING COMPANY, LIMITED, OF LONDON, ENGLAND

RADIATOR AND THE LIKE

Application filed August 18, 1930, Serial No. 476,133, and in Great Britain September 11, 1929.

This invention relates to radiators such as are used in central heating systems and relates more particularly to radiators of the "loop" type, that is to say, radiators which 5 are built up of a number of like sections having lateral communicating passages at the top and bottom and vertical or longitudinal waterways which in some cases are separated by an elongated central cavity.

10 An object of the present invention is to provide a form of radiator of the above type which is adapted to present a front (or back) surface area lying substantially in one plane and preferably so that it gives an appearance of a continuous or panelled surface suitable for use with (or without) a covering surface element or material such as a veneer as described in the prior British specification No. 297,043.

15 The invention broadly consists in a radiator of the type above described in which the contiguous sections are each formed with at least one flat face adapted, when the sections are assembled together, to lie in the same 20 plane as the flat faces of all or others of the series.

The invention further consists in the provision of a slot or recess (or a plurality thereof) in each (or some) of the sections to receive clips or securing means associated with the veneer as described in the prior British specification referred to above. The slots or 25 recesses may in some cases be replaced by equivalent means complementary to the devices employed in or associated with the veneer for securing purposes.

It is preferred where slots or recesses are employed to form them partly in one section and partly in another so that the slot 30 or recess is completed only when the complementary parts are fitted together in assembling a radiator.

According to one form the sections are each formed of a shape (in cross-sectional 35 plan) representing a **T**, that is to say, the stem of the **T** is constituted by the waterway portion while the cross-piece of the **T** is constructed with a flattened side of the unit and flanges which project preferably on both sides 40 thereof, the arrangement being such that

when the section units are assembled together to form a radiator the margins of the flanges nearly abut against one another leaving only a small clearance and the flanges, together with a portion of the body or waterway part, 55 enclose a vertical or horizontal passageway through which air can circulate.

Reference is made to the accompanying drawings illustrating one embodiment of the invention in which:—

Figure 1 is a fragmentary view of the front of a radiator adapted to receive a covering panel or veneer;

Figure 2 is a fragmentary plan view of the radiator shown in Figure 1 showing the 65 veneer in position;

Figure 3 is an end elevation showing an application of the invention in which the radiator is mounted beneath a window;

Figure 4 is a plan view of the arrangement 70 shown in Figure 3 with part of the window board broken away to show the radiator sections;

Figure 5 is a plan view of a modified form 75 of radiator;

Figure 6 is an end elevation of the radiator shown in Figure 5.

In carrying the invention into effect according to one convenient mode, as applied 80 by way of example for use in conjunction with veneers of the character described in the prior British specification referred to above, a plurality of sections 10 (Figure 1) are cast comprising the usual lateral pas-

85 sageway at the top and bottom for constituting the header way of the radiator and of a more or less rectangular shape in side elevation. They may be formed either with or

without a central vertical or longitudinal cavity. The front portion of each section is 90 cast with a flat face 11 which is extended on either side of the waterway by the formation of a pair of webs or flanges 12, these

95 webs or flanges extending to both sides of the central plane of the section. The maximum width of the flat face 11 is preferably slightly less than the maximum width across

the bosses 13 surrounding the through passageway at the top and bottom of the section 100 which serve to connect the like sections

on either side, so that a small clearance 14 is allowed between the edge of the flange of one radiator and that of the next.

Where the radiators are intended to be used in conjunction with veneers or covering elements as in the present instance, slots are provided in certain of the flat faces of the sections for receiving the clips 25 by means of which the veneer is supported. These slots are formed by recessing or rabbetting the edge of certain of the sections as at 15 so that when two such recessed sections are fitted together a rectangular shaped space 16 is enclosed which affords a lip over which the veneer clips 25, which are indicated by the dotted lines in Figure 1, may be fitted. The radiator sections are provided with appropriate recesses at places corresponding with the position of the clip securing means 20 on the veneer.

The assembly of the sections 10 to form a radiator provides clearances or cavities 17 through which the air can circulate freely behind the veneer 19 so that heat is not only radiated from the veneer surface but the convection currents are free to transmit heat from the cavity, recess or other position in which the radiator is installed.

In the arrangement illustrated in Figures 3 and 4 the radiator is located beneath a window and gratings 21 and 22 are provided in the skirting board and window board respectively for the circulation of air. Brackets 23 and stays 24 are provided for supporting the radiator but any other means may be used, if desired, and the radiators may also be mounted by the aid of resilient means such as described in the prior British specification No. 290,868. The veneer 19 is held in place by the clips 25 which engage in slots in the radiator as previously described and is further secured at the periphery by engagement with the skirting and window boards. Suitable connections are provided 45 for the circulation of the heating medium.

According to a modification of the invention for details of which reference is to be had to Figures 5 and 6, each of the sections 10 is formed with a relatively wide flange or face 11 and may be provided with one or more loops 26 for the circulation of the heating medium. The depth of the loops may be varied according to the heating requirements. The sections are provided with small connecting waterways 27 at the top and bottom and may be joined by a screwed or other nipple 28. Owing to the width of the flanges 11 of this form of radiator section the slots for the reception of the veneer securing clips 60 may be formed wholly within the face as indicated at 29 and such slots may, if desired be employed in addition to slots formed in two adjacent flanges as previously described.

In some cases it may be necessary for the production of satisfactory castings to have

an air way between the loops of a section as indicated at 30.

The mounting and general arrangement of this form of radiator is similar in all respects to that of the previous example.

It will also be understood that the veneer securing means may not be engaged directly with the radiator but may be arranged to co-operate with supports independent thereof, for example such supports could be built directly into the wall as shown in Figure 3 the veneer could be supported by the longitudinal members 31 and 32. An arrangement of this character may conveniently be employed in conjunction with the resilient mounting of 80 the radiator referred to above.

Having now described my invention what I claim as new and desire to secure by Letters Patent is:—

1. A radiator comprising a plurality of 85 loop elements each having one flat face adapted, when the sections are assembled together, to lie in the same plane as others of the series, and a removable panel element held in heat transference association with 90 said faces to act as a heat radiating surface.

2. A radiator comprising a plurality of 95 sections each having a flat face adapted for presentation to a veneer or removable panel and means formed in said faces for receiving 95 securing means associated with the veneer.

3. A radiator comprising a plurality of 100 sections each having a flat face adapted for presentation to a veneer or removable panel and an aperture formed partly in one face 100 and partly in an adjacent face for receiving securing means associated with the veneer.

4. A radiator comprising a plurality of 105 loop sections each having a flat face adapted, when the sections are assembled together, to afford a substantially plane heating surface directed towards the room space, means for supporting the radiator, a removable panel element, and means independent of the radiator supports for maintaining said panel in 110 heat transference relationship with the radiator.

5. A radiator comprising a flat face area 115 adapted for presentation towards the room space, a loop element formed integral therewith and projecting rearwardly of said face area to afford a heating surface for circulating air, and a removable panel element held in heat transference association with said face to act as a heat radiating surface.

6. A radiator comprising a flat face area 125 adapted for presentation towards the room space, a loop element formed integral therewith and projecting rearwardly of said face area to afford a heating surface for circulating air, an aperture formed in said face, and a removable covering panel held in heat transference association with the radiator and having securing means engaged in said aperture.

7. In a radiator installation, a radiator comprising an interrupted flat face area directed towards the room space, and a plurality of loop elements formed integral with portions of said face area and projecting rearwardly thereof, a removable covering panel held in heat transference association with said face area and elements of a decorative or similar nature surrounding said panel to conceal the edges thereof.

In testimony whereof I have signed my name to this specification.

FREDERICK HUGH AUSTEN.
